UNITED STATES PATENT OFFICE.

EDWIN H. PENDLETON, OF SAN FRANCISCO, CALIFORNIA, ASSIGNOR TO HOME MANUFACTURING COMPANY, A CORPORATION OF CALIFORNIA.

DESIGN FOR A CHILD'S CAR.

53,934.

Specification for Design.

Patented Oct. 7, 1919.

Application filed March 3, 1919. Serial No. 280,475. Term of patent 7 years.

To all whom it may concern:

Be it known that I, EDWIN H. PENDLETON, a citizen of the United States, and a resident of the city and county of San Francisco and State of California, have invented a new, original, and ornamental Design for a Child's Car, of which the following is a specification, reference being had to the accompanying drawing, forming part thereof.

In the drawing:

Figure 1 is a plan view of the car,
Fig. 2 is a rear elevation of the car, and
Fig. 3 is a side elevation of the car on a
slightly smaller scale than Figs. 1 and 2.

What I claim is:—

The new and ornamental design for a child's car, substantially as shown.

In testimony whereof, I have hereunto set my hand this 26th day of February, 1919, in the presence of the two subscribed witnesses.

EDWIN H. PENDLETON.

Witnesses:

CARLOS P. GRIFFIN,
EDWIN E. DEWING.
